UNITED STATES PATENT OFFICE.

LEWIS S. HODGDON, OF BANGOR, MAINE.

PRICE EXHIBITOR.

Application filed January 27, 1922. Serial No. 532,085.

To all whom it may concern:

Be it known that I, LEWIS S. HODGDON, a citizen of the United States, and resident of Bangor, county of Penobscot, State of Maine, have invented an Improvement in Price Exhibitors, of which the following description, in connection with the accompanying drawings, is a specification, like characters on the drawings representing like parts in each of the several views.

This invention relates to changeable signs, and while having other and more general fields of usefulness is well adapted and designed as a price exhibitor for articles of merchandise in a store or shop. A principal object of the invention is to provide a price exhibitor or the like that may be cheaply manufactured and being capable of selective adjustment quickly and easily to exhibit any one of a wide range of price marks for goods to which it is applied. The foregoing and other objects and advantages of the invention will more fully appear from the following detailed description taken in connection with the accompanying drawings, and the distinctive features of novelty will be pointed out in the appended claims.

Referring to the drawings:

Fig. 1 is an elevation of a price exhibitor embodying the invention;

Fig. 2 is an edge view thereof;

Fig. 3 is an elevation similar to Figure 1 but showing the device mounted on a special base and holder co-operative therewith;

Fig. 4 is an end view of the device as assembled in Figure 3;

Fig. 5 is a transverse section on a relatively enlarged scale; and

Fig. 6 is a detail elevation of an elbow shutter employed with the invention.

10 indicates a housing or body of sheet material of a relatively deep U-shape with parallel flat sides. This housing may be made of cardboard or the like or it may be made of other more durable material such as metal. One side of this housing of which may be considered its back is extended upward a substantial distance above its front side as indicated at 10^a. This housing is of a length to permit the pivoting therein of a number of sets of cards or slips corresponding to the number of figures in dollars and cents which it is desired the device shall be capable of exhibiting. As illustratively shown four of these columns in-

dictated at 11 are provided, each consisting preferably of ten cards marked with figures running from 0 to 9. Each of these sets of cards are suitably pivoted at their tops to 60 the back of the housing, this being accomplished as shown by eyelets 12 suitably headed to hold the cards in place. These eyelets do not extend through the front side 10^b of the housing which is thus capable of being 65 yieldingly pressed outward to a greater or less extent so as to obtain access to the cards which depend within the housing from the pivots 12. The sets of cards 11 are thus normally enclosed within the housing and 70 concealed by the front 10^b thereof. To exhibit any required price sign it is only necessary to swing upward the cards bearing the proper figures from each set so that these cards extend upward from their pivots and 75 with the housing extension 10^a as a background. This housing extension is provided with suitable marks to be read in conjunction with the figures exhibited. These marks may consist of a dollar sign at the left side 80 as indicated at 13, and one or more decimal point marks two of these being shown as indicated at 14, while adjacent the right hand side a mark 15 indicating cents may be placed. This cents mark is illustratively 85 shown as in juxtaposition to the third set of cards, the advantage of this being that when a price in cents only is exhibited, i. e. consisting of two figures it will be symmetrically placed intermediate the ends of the 90 device. For concealing all of these marks on the extension back 10^a except those required in each particular case, I provide a series of L shutters 16 pivoted to the respective pivots 12 and adapted to be swung 95 up to cover the several marks, or downward to exhibit them selectively as required. My invention also comprehends a special holder for the housing body 10 adapted to keep the housing with its cards normally upright and 100 also frictionally and detachably held in assembled relation. For this purpose I provide a holder base 17 with a curved or part cylindrical bottom surface. This base has a socket 17^a formed in its upper side from 105 which cheek plates 18 extend upwardly in spaced apart relation. These cheek plates are approximately parallel and they may be made of sheet metal or other material exhibiting a spring property. The housing 10 is adapted to be pressed between these plates 110 18 to be frictionally held thereby. The

holder base 17 is of relatively heavy construction while the housing 10 with its cards is relatively light, and thus the base 17 will normally hold the exhibitor upright, 5 and if it should be displaced casually, as often happens as a clerk reaches for goods, it will at once right itself and return the sign to upright position. It will be understood that the sets of cards 11 and the L 10 shutters 16, being of relatively light stock may be held frictionally on their pivots 12 in adjusted position, though it is within the contemplation of the invention to provide suitable means for holding the cards as they 15 are placed when desired. In this as well as other particulars the present embodiment is understood to be merely illustrative and not restrictive, reference being had to the appended claims rather than to the foregoing 20 description to indicate the scope of the invention.

Having described my invention, what I claim as new and desire to secure by Letters Patent is:

- 25 1. A price exhibitor or the like comprising a housing having pivotally mounted therein a plurality of sets of cards with provision whereby selective ones of the cards of each of said sets may be moved to an exhibiting 30 position or concealed at will, the arrangement of said cards being such that when selected ones of different sets thereof are moved to exhibiting position they each present component parts of a unitary indicia 35 to denote a price or the like.
2. A price exhibitor or the like comprising a housing having a plurality of sets of cards pivoted thereon with each set upon a sepa-

rate pivot, with said cards normally concealed within the housing, said housing arranged to permit selected cards of each set to be moved to an exhibiting position, or to be concealed at will, the cards of each set bearing a range of component parts of a composite price indicia whereby a given 45 price reading may be provided by moving selected cards of the respective sets to an exhibiting position.

3. A price exhibitor comprising a housing with front and back sides and with its back 50 provided with an extension, and a plurality of sets of cards each bearing a component part of a composite price indicia, mounted with each set on a separate pivot borne by the back of said housing normally in a concealed 55 position but capable of having selected cards of each set swung into exhibiting position against the back extension of the housing, whereby the cards in exhibiting position together display a desired price mark.

4. A price exhibitor comprising a housing with front and back sides, and with its back provided with an upward extension, and a plurality of sets of cards each bearing a price 65 indicia mounted on separate pivots borne by the back of said housing, normally depending therein but capable of being swung upwardly into exhibiting position, the back of said housing bearing markings to be read with the indicia on said cards and equipped 70 with means for selectively concealing such markings.

In testimony whereof, I have signed my name to this specification.

LEWIS S. HODGDON.
